FOLDING CHAIR

Ben Shwayder, Ecorse, Mich.

Application February 27, 1936, Serial No. 66,035

1 Claim. (Cl. 155—142)

My invention relates to a new and useful improvement in a folding chair and has for its object the provision of a folding chair which will be simple in structure, economical of manufacture, durable and highly efficient in use.

Another object of the invention is the provision of a folding chair whereby the legs may be folded into compact relation so that the chair will occupy a minimum amount of space when folded.

Another object of the invention is the provision of a folding chair so constructed and arranged that in its movement from folded to unfolded position and vice versa the action will be a smooth, easy and quiet one.

Another object of the invention is the provision in a folding chair of a structure which lends itself admirably to the mounting of upholstery thereon.

Another object of the invention is the provision in a folding chair of a construction so arranged that when in unfolded position the supporting legs will be extended diagonally to each other and so that when moving from folded to unfolding position and vice versa one pair of legs will swing on a swingable member pivotally mounted on the other pair of legs.

Another object of the invention is the provision in a folding chair of this class of means for pivotally mounting the seat between a pair of legs and utilizing the mounting means for spacing the side of the chair from the legs.

Another object of the invention is the provision in a folding chair of this class of a hinge member doubled upon itself and having one doubled-over portion so constructed as to form a pivot and the other so constructed as to prevent pivoting thereon when cooperating with a suspended part.

Another object of the invention is the provision in a tubular folding chair of re-enforcing rails projected between the tubular parts of the chair and re-enforced by rods or cores extended therethrough.

Another object of the invention is the provision in a chair of this class of re-enforcing rods extended therethrough and welded at opposite ends to the re-enforcing portions.

Another object of the invention is the provision in a chair of this class of a back-forming portion so constructed and arranged that it may be easily and quickly mounted in position and removed therefrom and so constructed and arranged that the upholstery thereon may be easily and quickly attached thereto.

Another object of the invention is the provision in a chair of a seat supporting member and a seat so constructed and arranged that the seat may be easily and quickly mounted in position and removed therefrom.

Another object of the invention is the provision in a chair seat of a supporting frame so constructed and arranged as to engage the holding frame in such a manner as to require a minimum amount of strength in the attaching parts used.

Another object of the invention is the provision in a chair seat of a seat frame so constructed and arranged as to lend itself to an easy and inexpensive method of upholstering.

Another object of the invention is the provision in a folding chair having a seat of means carried between said portion and one of the legs adapted for cooperating and resisting swingable movement of the seat in one direction beyond a predetermined distance.

Another object of the invention is the provision in a chair having tubular supporting legs or other parts so constructed and arranged as to be easily and quickly closed with suitable closing tips.

Another object of the invention is the provision of a chair so constructed and arranged that distortion or swaying resulting from side strains delivered to the chair is reduced to a minimum so that a rigid structure is provided.

Another object of the invention is the provision in a chair of a removable back so arranged and constructed that the upholstery may be very easily and quickly locked thereon.

Other objects will appear hereinafter.

The invention consists in the combination and arrangement of parts hereinafter described and claimed.

The invention will be best understood by a reference to the accompanying drawings, which form a part of this specification, and in which,

In the drawings I have illustrated the invention applied particularly to a tubular folding chair, that is a chair in which the supporting parts are formed from tubes. Experience has shown that this type of structure provides a chair which is light and possessed of a maximum amount of strength. There are features of the invention, however, which will appear from the description which may be used to equal advantage with parts other than tubular parts and, of course, as to these features I do not wish to limit myself to a tubular chair construction.

In the drawings I have illustrated a chair having supporting legs formed from a tubular piece of material doubled upon itself to provide the U shaped structure and form the supporting legs 24 and 25 connected at their top by the bight 26 of the U shaped structure, this bight 26 forming the upper rail of the chair back and the legs 24 and 25 above the seat portion forming the back supporting side rails. A seat supporting frame is formed by doubling a piece of tubular material upon itself to provide a U shaped structure, each of the legs 27 of the U shaped structure forming the side rails of the seat supporting structure and the bight 28 forming the front rail of the seat supporting structure. Each of the side rails of the seat frame is pivotally mounted in the same manner as shown in Fig. 4. Projected through the supporting leg 24 or 25, as the case may be, is a pin 29 which is upset as at 30 at one end to rivet the pin in position on the supporting leg. Formed preferably integral with this pin 29 is a boss 31, which serves as a spacing body to space the supporting leg 24 or 25, as the case may be, from the side rail 27 of the seat supporting frame. This pin 29 at the opposite side of the boss 31 projects through the side rail of the seat supporting frame and is upset as at 32 to rivet the pin in position and thus pivotally mount the seat supporting frame between and spaced from the legs 24 and 25.

Rear or bracing legs 33 and 34 are provided 65 and each of these legs is connected at its upper end to its respective side supporting leg 24 or 25, the connection in each case being the same. In Fig. 2 and Fig. 9 this form of connection is believed clearly shown. To make the connection 70 I use a U shaped, hinge-forming clip comprising the bight 35 and the legs 36 and 37. The leg 36 is projected through the supporting leg 24 or 25 and upset as at 38 to rivet the structure in position. This leg 36 is preferably circular in cross 75 section and serves as a pivot on which the clip

may swing on the supporting leg 24 or 25. The opposite leg 37 is provided with the flat portions 39 and 40 and is projected through the leg 33 or 34, adjacent the upper end. The opening in the leg 33 or 34 through which the leg 37 is projected is also provided with oppositely disposed flat edges, so that the leg 33 can not pivot on the leg 37 of the clip. The upper ends of the legs 33 and 34 are closed by a suitable cap which comprises the semi-spherical portion 41 and the tubular neck 42 which is insertable into the end of the tube forming the leg 33 or 34. The opening formed in the cap through which the leg 37 of the U shaped clip projects is also provided with flat edges to assist in preventing rotation of the leg 33 or 34 on the leg of the U shaped clip. The leg 37 of the U shaped clip is also upset as at 43 so that the device is securely riveted in position. This method of attaching the legs 33 and 34 to the legs 24 and 25, respectively, performs an important function in the invention so far as obtaining a structure which will fold into compact form is concerned. The legs 33 and 34 are illustrated in Fig. 2 as folded into engagement with the legs 24 and 25 and it will be noted that the legs 33 and 34 when in this folded, compact position engage and lie in engagement throughout their lengths with the legs 24 and 25. When swinging in this position the hinge forming clip swings on the leg 36 as a pivot. In moving the legs 33 and 34 from the folded position as shown in Fig. 2 to the operative position as shown in Fig. 1, the bight of the clip will swing upwardly so that the legs 33 and 34 will move bodily outwardly from the legs 24 and 25 for a short distance, and at the same time, move upwardly, the bight 35 moving toward the position at which it would extend at right angles to the longitudinal axis of the leg 24 or 25 as the case may be. It is obvious that further upward swinging will effect a tilting of the legs 33 and 34 to the respective legs on which they are mounted. It will be noted that the bight 35 of the U shaped clip always extends at an inclination to the longitudinal axis of the leg 33 or 34 to which it is attached, but its angularity to the leg 24 or 25 to which it is attached varies as the legs 33 and 34 are moved relatively to the legs 24 and 25.

Projecting outwardly from the outer surface of each of the frame rails, adjacent the rear end thereof, is a stop plug 44 which is a head formed on the end of the pin 45 which projects through the side rail 27 of the seat supporting frame. This pin 45 at the opposite side of the boss 31 projects through the side rail of the seat supporting frame and is upset as at 46 to rivet the pin in position and thus pivotally mount the seat supporting frame between and spaced from the legs 24 and 25.

The lugs 47 serve to limit the thrust of the member 47 as shown in Fig. 16. In the modified form shown in Fig. 14 the arm 46, which corresponds to 46, is doubled upon itself as at 48. The mounting of the arm otherwise is the same. This doubled-over portion 48 serves to engage the seat frame rather than a stop plug carried by the frame.

Extending between the legs 33 and 34 to re-

enforce and strengthen these legs and prevent distortion and twisting is a brace. A similar brace extends between the legs 24 and 25 and the mounting of each of these braces is the same.

5 The brace comprises a tube 49 which engages at its opposite ends the inner faces of the legs between which it is positioned. Projecting through this tube 49 is a rod 50 which is spot welded at points to the tube 49. This rod projects through 10 the legs between which it is positioned, as clearly shown in Fig. 12, and is upset at its outwardly projecting end to rivet the structure firmly together.

In the structure shown in Fig. 1 I have illustrated the seat supporting frame provided with an upholstered seat. This seat comprises a frame preferably formed of wood. The frame is of the closed frame type and the side rails and front rails are of the structure shown in Fig. 3. 15 Each of the side rails and the front rails comprises the body 51 which is concaved as at 52 to provide the overhanging lip 53. This concavity conforms to the curvature of the tubes or the material from which the seat supporting frame 20 is made so that the lip 53 will overhang the seat supporting frame. Screws 54 are projected through the frame rails 27 to secure the seat in position. A covering 55 is also held securely in position by the frame to retain the upholstering 25 30 56 and such spring arrangement as may be desired for a cushion of this kind. In Fig. 15 I have shown the seat provided with the spring members 151 which are connected to oppositely disposed side rails and span the space therebetween. Thus, there is provided a seat for a folding chair which is upholstered and provided with a spring cushion. The seat supporting frame is, of course, open at its rear so that the seat may be slid inwardly from the rear and secured in position. Since the overhanging tongue 53 bears 35 down upon the frame it is obvious that a strong and rigid support for the seat is thus provided. It is also obvious that the seat itself may be very easily and quickly removed and replaced, thus 40 45 facilitating such operations as might become necessary for upholstering or redecorating.

In both of the forms illustrated I have indicated a back to the seat which comprises a panel 59 which is suitably formed to conform to the curvature of the person's back. In the form shown in Fig. 11 which is the back indicated in Fig. 10, no upholstering is used but in the form shown in Fig. 1 and in Fig. 8 upholstering is used. In both instances, however, the back panel itself is 50 55 formed substantially the same. The lower edge of the back panel 59 is curled upon itself to provide a knuckle or sleeve 60. The other edges of the panel 59 are doubled backwardly and this doubled backwardly portion 61 is curved to conform to the rail 26 which is the bight of the U shaped structure of which the supporting legs 24 and 25 form a part. Intermediate the edges of this curved, rearwardly extended portion 61 there is pressed a trough shaped structure 62. Suitable screws 63 may be projected through the rearwardly turned portion into the bight 26 and the upper portion of the legs 24 and 25 to secure the back in position. By removing these screws the back may be very easily and quickly removed as 60 65 70 75 a unit and replaced in position. It will be noted that by forming the rearwardly turned portion in this manner, there is provided the part 61 which engages in front of the bight 26 and the upper portions of the legs 24 and 25 so that pressure exerted upon the back is thus directed against

these portions of the legs and the bight 26 which form a supporting frame for the back.

In the form shown in Fig. 1 and Fig. 8 the rear side of the back is covered with a layer 65 of leather or other suitable upholstering material. The front face is also covered with a layer 66 of leather or other suitable upholstering material and this layer is secured at its lower edge to the cord 67 which is slipped into the sleeve or knuckle 60. The layer 66 of the upholstering is then drawn around the upper edges of the back and the side edges of the back and laid over the trough 62 into which this layer of upholstering may be pressed by forcing the cord strip 68 into position. This cord strip will serve to lock this 15 upholstering in position and securely engage it while at the same time the upholstering may be very easily and quickly removed by removing the locking strip so that it is a very simple matter to reupholster a seat constructed in this manner. 20 The layer 65 is held in position in the same manner as is the layer 66.

The bottoms of the tubular members are also closed with caps 41', each having the inwardly projecting neck 42' which inserts into the tube. 25 In each of these necks there is provided an opening 72 in which is adapted to engage the tongue 73 which is punched inwardly from the lower end of the tube in which the cap is inserted. If desired, the tongue 73 may be forced inwardly 30 with a punch after it has snapped into a hole 72. Thus the mounting of these closures is a simple and easy operation which provides the rounded ends for the open tubes.

In Fig. 10 I have illustrated the seat frame 35 formed from flat metal and embodying the side rails 27' and the front rail or bight 28'. In this frame is mounted the seat 74 which may be upholstered or not, as desired. In Fig. 14 I have illustrated a slightly different form of brace in 40 which a straight rod 75 is projected into the oppositely disposed legs with which used but not through these legs, the inner ends abutting against the tubes. The rod 75 is re-enforced by a rod 76 which is upwardly offset, intermediate 45 its ends and welded to the rod 75 at its central portion 77, thus forming a combined truss and beam arrangement. The ends of this rod 76 also project through openings formed on the inner side of the tubular legs and the ends of the rods 50 are welded to the tube with which used. This is a slightly modified form of bracing but it has been found that this form, as well as the form shown in Fig. 1 and Fig. 10, is most effective in 55 resisting side strains and preventing a weaving of the chair when placed under side strains.

As shown in the drawings I prefer to use a tubular body in which the edges are overlapped, as clearly appears in Fig. 12 and bound together at 78. However, any sort of tube may be used. 60 The outer side of the tube is provided with a channel or groove 79 which serves as a countersink for the screw heads. It is believed obvious that if it is not desired to form the groove, the tube may be impressed at the definite locations 65 of the screws to form the necessary space for countersinking so that there is no obstruction projecting outwardly from the surface of the chair. This prevents catching of the clothes on the chair and adds considerably to the appear- 70 75 ance.

While I have illustrated and described the preferred form of construction, I do not wish to limit myself to the precise details of structure shown, but desire to avail myself of such variations and 75

modifications as may appear within the scope of the appended claim.

Having thus described my invention, what I claim as new and desire to secure by Letters 5 Patent is:

In a folding chair, a pair of spaced supporting legs, a seat positioned between and pivotally mounted, intermediate its ends, on said legs, a second pair of spaced legs adapted, when in use, 10 to extend at an angle to said first mentioned pair of legs, means for connecting the upper end of each of said second pair of legs to one of said first mentioned legs at a point above the position of

mounting of said seat, said connecting means comprising a U-shaped clip inwardly of the legs and having one arm thereof pivotally attached to one of said first mentioned legs and the other arm thereof fixed to one of said second mentioned legs, an arm pivoted at one end thereof to said seat and pivotally mounted at its opposite end to one of said second pair of legs, and an abutment member carried by said seat for engaging said arm upon swinging movement of the front 10 of said seat downwardly a predetermined distance.

BEN SHWAYDER.
